[57] CLAIM

The ornamental design for a housing for a battery or
similar article, as shown and described.

DESCRIPTION

FIG. 1 is a top, front, and right side perspective view of
said housing for a battery or similar article showing my
new design, where the broken line material is for illustrative
purposes and forms no part of the claimed design;

FIG. 2 is a left side elevational view thereof, the right
side elevational view thereof being a mirror image;

FIG. 3 is a rear elevational view thereof, where the
broken line material is for illustrative purposes and
forms no part of the claimed design; and

FIG. 4 is a bottom plan view thereof.
